UNITED STATES PATENT OFFICE.

HENRI BOBST, OF LAUSANNE, SWITZERLAND, ASSIGNOR TO J. BOBST & FILS, SOCIETE ANONYME, OF LAUSANNE, SWITZERLAND, A CORPORATION OF SWITZERLAND.

APPARATUS FOR WORKING PAPER, CARTON, AND THE LIKE MATERIALS.

Application filed January 19, 1924, Serial No. 687,397, and in Switzerland January 26, 1923.

This invention relates to an apparatus for working paper, card, or other like materials.

It comprises a machine for working the material and a feeding mechanism provided with an automatic feed table, this feed table being subject to the action of a mechanism which allows it to be moved into a raised position, so as to provide a free space 10 to allow of passing between the machine for working the material and the feed.

The accompanying drawing illustrates the invention in one construction, given by way of example.

15 Fig. 1 is an elevation (of the side opposite to the control) showing in part a feed apparatus and a shaping machine; the automatic feed table is in operation and the hand feeding table is in the lowered position.

20 Fig. 2 is a sectional elevation of the feed and of the shaping machine, the automatic feed table being raised, or out of operation, and the table for hand feeding being 25 in the operating position.

25 Fig. 3 is a plan view (of the control side) showing the hand feeding table raised, the feed control, the part above the line $a - a'$, of Fig. 2 being omitted for the sake of 30 clearness.

35 Fig. 4 is a plan view (of the side opposite the control) showing the automatic feed table and the hand feed table lowered, the locking mechanism and the means for raising the automatic feed table.

40 Fig. 5 illustrates the mounting of the feed as seen from the side where the pile of paper stands.

Figs. 6 and 7 illustrate details of this 45 mounting in different positions.

Fig. 8 is a section on the line $b - b'$ of Fig. 5 of the mounting in the position of rest.

The assembly illustrated in Fig. 1 shows 50 at the right hand side the automatic feed apparatus A with an automatic feed table 1 and at the left hand side the shaping machine B with a hand feeding table 2.

55 The automatic feed table 1 (Fig. 1) receives the sheets taken by the layer-on from the pile of paper 3. Its purpose is to transport the sheets and to place them in correct position before they are taken by the shaping machine. The means for separating the sheets and for putting them in position

are not illustrated, but only the belts 4 which 55 serve to transport the sheets and the roller 5 which drives the belts are indicated in Figs. 1, 2 and 4. The supports 6 of the automatic feed table are connected together by ties 8 and 9 at one end and at the other 60 by the roller 5. They pivot about the principal shaft 10 which is carried by the members 11 and 12 of the feed frame. The automatic feed table is connected to the shaping machine by bolts 13 and 14, which are fixed 65 upon a shaft 15 adapted to turn in the members 16 and 17 of the frame of the shaping machine. The lever 18 pinned in the shaft 15 allows the bolts to be operated.

Two toothed sectors 19 mounted on the 70 supports 6 engage with teeth 21 formed in a shaft 23 adapted to turn in the members 11 and 12 of the feed frame. A wheel 24 keyed on the shaft 23 is driven by a pinion 25 rigid with a crank 26 capable of turning 75 freely on a stub shaft 27 (Fig. 4), a pawl 28 preventing its rotation in one direction.

80 A pulley 29, by means of gearing 30, 31 and 32 operates the shaping machine and a bevel gear 33, 34, 35 and 36 operates a control pinion 37 of the feed apparatus. The pinion 37 turns idly on the shaft 38 rigidly mounted on the member 12 of the feed frame and drives a wheel 39 mounted idly on the 85 principal shaft 10 of the feed, as also a gear 40, through a gear 41 and shaft 42. In the lowered position of the automatic feed table 1, a gear 43 mounted on the end of the roller 5 engages with the gear 40, thus actuating the roller 5 and the belts 4 (Fig. 2). 90

95 The shaft 10 of the feed carries cams and gears which operate the various parts, that are not illustrated, of the feed and of the automatic feed table. The shaft 10 is driven by the gear 39 (Fig. 5) by means of a clutch which is engaged or disengaged by means of a lever 44, which is keyed on one end of a shaft 45 adapted to rotate in the members 11 and 12 of the frame and carrying at its other end a cam 46. When the clutch is 100 engaged, the lever 44 is moved into the position 44¹ (Fig. 1) and this causes the cam 46 to act on a roller 47 of a lever 48. The lower end 49 of the lever 48 is crescent shaped, and takes the position indicated at 50 in Fig. 8. A roller 51 mounted on the sleeve 52 of the clutch is then freed by the crescent shaped end 49. Under the action 105

of a spring 53 the clutch sleeve slides lengthwise of the shaft 10 and the feather 54 until the slot 55 engages with the tooth 56 of the wheel 39, which causes the rotation of the shaft 10. To disengage the clutch, the lever 44 is moved into the position indicated in Fig. 1, the crescent end 49 under the action of the spring 57 takes up the position illustrated in Fig. 7. The roller 51 in the course of its rotation rises on the inclined plane 58 (Fig. 5) of the crescent end and produces the disengagement of the parts 55 and 56. Upon disengagement of the clutch, a roller 59 (Fig. 7) mounted on a double lever 60 pivoted upon the lever 48 comes in contact with a crown 61, under the action of a spring 62. At the precise moment when the clutch parts disengage, the roller 59 is opposite to a slot 63 in the crown 61. The tension of the spring 62 causes the roller 59 to move to the bottom of the slot 63, which produces a supplementary rotation of the crown 61 and of the shaft 10, the crown being rigidly mounted upon the latter by means of the key 54. The effect of this rotation is to increase the separation of the clutch parts 55 and 56, the roller 51 of the clutch sleeve continuing for this reason to travel on the inclined plane 58. The stopping position is illustrated in Fig. 6. At this moment the roller 59 has reached the bottom of the slot 63 and thus holds the shaft 10 in a predetermined position, whatever the speed of rotation of the wheel 39. On engagement, the lever 60 which carries the roller 59 strikes against a pin 64 which causes the roller 59 to move out of the slot 63 before the crescent end 49 allows the roller 51 to escape from the clutch sleeve (Figs. 6 and 8).

The arms 65 and 66, pinned upon a shaft 67 adapted to turn in the members 16 and 17 of the shaping machine frame, support the hand feeding table 2 (Fig. 1). The arms 65 and 66 are provided with slots 68 into which enter the bolts 70 and 71 for keeping the table 2 in the hand feeding position (Fig. 2).

The bolts 70 and 71 pinned on the shaft 15 are operated by the lever 18.

The operation of the automatic table is as follows:

When the lever 18 is operated, bolts 13 and 14 release the supports of the automatic feed table 1, which turns about the shaft 10 upon the crank 26 being turned. The space obtained between the feed table 1 and the shaping machine B allows an operator to pass between the two machines.

If hand feeding is to be carried on, the table 2 is raised into the place of the automatic feeding table (Fig. 2) and is kept in position by the bolts 70, 71 operated by means of the lever 18. The sheets taken from the pile 3 are freed from the roller

5 by the turning of the automatic feed table, and are put in position by hand before being taken by the shaping machine.

The turning of the automatic feed table 1, according to Fig. 2, stops the rotation of the roller 5, owing to the fact that the gear 43 becomes disengaged from the gear wheel 40. The operation of the parts of the feed and of the automatic feed table is stopped when the rotation of the shaft 10 is stopped by placing the disengaging lever 44 in the lower position which allows the shaping machine to operate alone, the wheel 39 then turning idly on the shaft 10 and the gear 43 being out of engagement with the wheel 40. When the automatic feed table is lowered and is held by the bolts 13 and 14, only the shaping machine and the transporting belts 4 can be operated, the lever 44 in its lower position stopping the parts of the feed and of the automatic feed table.

When the lever 44 is raised into the position 44¹ and is then lowered, one or more sheets can be passed through the shaping machine at predetermined intervals without stopping the machine. Since a revolution of the shaft 10 causes the movement of the feed parts required for displacing one sheet, one sheet will pass into the shaping machine or other paper working machine at each revolution of this shaft.

On disengagement of the roller 59 entering the slot 63 causes a supplementary separation of the clutch parts 55 and 56 and stops the shaft 10 always exactly in the same position whatever may be the speed of rotation of the wheel 39.

Instead of being pivoted upon the paper working machine, the hand feeding table 2 may be similarly mounted upon the feeding machine.

What I claim is:

1. In an apparatus for working paper, card and similar materials the combination, with a machine for working, of a feeding machine provided with an automatic feeding table carrying all the transporting mechanism serving for the automatic feed of the working machine, said table being pivoted to the main shaft of the feeding machine, a mechanism by means of which said table may be moved into a raised position, so as to produce a free space to allow a passage between the working machine and the feeding machine, elements actuating the transporting mechanism which are mounted upon the table, said elements being so disposed that during the pivoting of said table into its upper position the said transporting mechanism mounted on the table is automatically uncoupled.

2. In an apparatus for working paper, card and similar materials the combination, with a machine for working, of a feeding machine provided with an automatic feeding

table carrying all the transporting mechanism serving for the automatic feed of the working machine, said table being pivoted to the main shaft of the feeding machine, 5 a mechanism by means of which said table may be moved into a raised position, so as to produce a free space to allow a passage between the working machine and the feeding machine and a hand feeding table mov- 10 ably mounted whereby it can be brought when the automatic feed table occupies the raised position, into the place of the latter and can be held in this position.

3. In an apparatus for working paper, 15 card and similar materials the combination, with a machine for working, of a feeding machine provided with an automatic feeding table carrying all the transporting mechanism serving for the automatic feed of the 20 working machine, said tab'e being pivoted to the main shaft of the feeding machine, a mechanism by means of which said table may be moved into a raised position, so as to produce a free space to allow a passage 25 between the working machine and the feeding machine and a hand feeding table mov- ably mounted on the working machine, whereby it can be brought when the automatic feed table occupies the raised position, 30 into the place of the latter and can be held in this position.

4. In an apparatus for working paper, 35 card and similar materials the combination, with a machine for working, of a feeding machine provided with an automatic feeding table carrying all the transporting mechanism serving for the automatic feed of the working machine, said table being pivoted to the main shaft of the feeding machine, 40 a mechanism by means of which said table may be moved into a raised position, so as to produce a free space to allow a passage between the working machine and the feeding machine, a hand feeding table mounted 45 upon a shaft adapted to turn in the frame of the working machine, whereby said table can be brought, when the automatic feeding table occupies the raised position into the place of the latter, and a bolting arrange- 50 ment for keeping said hand feeding table in its raised position, whereby sheets can be taken in said position from a pile liberated by the elevation of the automatic feeding table and can be p'aced by hand in position 55 before they are taken by the working machine.

5. In an apparatus for working paper, 55 card and similar materials the combination, with a machine for working, of a feeding machine provided with an automatic feeding table carrying all the transporting mechanism serving for the automatic feed of the working machine, said table being pivoted to the main shaft of the feeding machine, 60 a mechanism by means of which said table

may be moved into a raised position, so as to produce a free space to allow a passage between the working machine and the feeding machine, and a hand feeding table mov- 70 ably mounted on the working machine whereby it can be brought, when the automatic feeding table occupies the raised position into the place of the latter and can be held in this position, and bolting arrangements for holding the automatic feeding 75 table in its working position, by bolting it to the working machine and the hand feeding table in the working position of the automatic feeding table by bolting it to the working machine, said bolting arrangements 80 being mounted on a common shaft and each comprising at least one bolt.

6. In an apparatus for working paper, 85 card and similar materials the combination, with a machine for working, of a feeding machine provided with an automatic feeding table upon which is mounted the whole transporting mechanism and which is mounted upon supports pivoted on the main shaft of the feeding machine and a mecha- 90 nism by means of which said table may be moved into a raised position, the actuating mechanism for the transporting mechanism mounted on the feeding table being so disposed that the transporting mechanism shall 95 be automatically uncoupled when the table attains the upper position, so as to produce a free space to allow a passage between the working machine and the feeding machine.

7. In an apparatus for working paper, 100 card and similar materials the combination, with a machine for working, of a feeding machine provided with an automatic feeding table mounted upon supports pivoted on the principal shaft of the feeding machine, and 105 a mechanism by means of which the table may be moved into a raised position, said mechanism comprising two pinions engaging with two sectors and keyed upon a shaft adapted to turn in the frame of the feeding machine, this shaft being controlled by a crank and a reducing gear.

8. In an apparatus for working paper, 115 card and similar materials the combination, with a machine for working, of a feeding machine provided with an automatic feeding table carrying a roller which drives trans- porting belts and is provided with a driving pinion and a mechanism by means of which the table can be moved to a raised position 120 in which the pinion is out of engagement with its control gear, so that the operation of the roller is arrested.

9. In an apparatus for working paper, 125 card and similar materials the combination, with a machine for working, of a feeding machine provided with an automatic feeding table mounted upon supports pivoted on the main shaft of the feeding machine, whereby it may be moved in a raised posi- 130

tion, said shaft being adapted to control the several parts of a distributor and of the automatic feeding table of the feeding machine and receiving its movement of rotation 5 through a clutch connection adapted to connect with the shaft a toothed wheel controlled by the working machine, a hand lever serving for engaging and disengaging the clutch and acting upon an engaging and dis- 10 engaging lever, the lower part of which carries a lever that is subjected to the action of a spring, said lever carrying a roller which on that disengagement of the clutch is adapted to roll upon a crown keyed upon the main 15 shaft, and to enter a slot in the crown at the precise moment when the clutch parts disengage, whereby a supplementary separation of the clutch parts and the stopping of the main shaft in a given position are caused, 20 whatever may be the speed of rotation of this shaft.

10. In an apparatus for working paper,

card and similar materials the combination, with a machine for working, of a feeding machine provided with an automatic feeding 25 table which can be moved into a raised position and carries a roller driving transporting belts and receiving its movement, when the said table is in its lower position, from gears directly driven from the working machine without passing through a clutch of the feed, whereby the working machine and the roller can operate without causing the other parts of the feeding machine and of the feeding table to operate, these latter 30 parts being set in operation by the engagement of the clutch, the revolution of the main shaft of the feeding machine corresponding to the passage of one sheet through the working machine. 40

In testimony whereof I have affixed my signature.

HENRI BOBST.
